Primary Examiner — Daniel Bui*Assistant Examiner* — Andrew Kerr(74) Attorney, Agent, or Firm — Wang Law Firm, Inc.(57) CLAIM

The ornamental design for a water bottle, as shown and described.

DESCRIPTION

FIG. 1 is a perspective view of a water bottle, showing my new design;

FIG. 2 is a front view thereof;

FIG. 3 is a left view thereof;

FIG. 4 is a back view thereof;

FIG. 5 is a right view thereof;

FIG. 6 is a top view thereof; and,

FIG. 7 is a bottom view thereof.

The broken lines in the drawing views represent unclaimed portions of a water bottle, which are included for the purpose of illustrating unclaimed environment only, and forms no part of the claimed design.
